AUTOMATIC LOCK OPERATION INDICATOR
FOR KEYSSebastian Merkl, New York, N. Y., assignor of
one-third to Jan Leyenaar, New York, N. Y.

Application November 22, 1938, Serial No. 241,733

8 Claims. (Cl. 70—395)

This invention relates to new and useful improvements in an automatic lock operation indicator for keys.

The invention has for an object the construction of an indicator associated with a key for a lock and adapted to indicate whether the key was used, the last time, to open or close the lock.

More specifically, the invention embodies an arrangement whereby when the key is used to close the lock the word "Closed" appears on the indicator so that at any time thereafter upon examination of the key one would know that the lock has been closed. It is also proposed to arrange the indicator to display the word "Open" and to obscure the word "Closed" when the key is used to open the lock.

Many people are uncertain a moment after they have left their homes or other establishments whether or not they locked the door. In order to remove this uncertainty, it is proposed that the person need only examine his key to ascertain whether or not the lock has been closed.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an automatic lock closing indicator and key constructed according to this invention.

Fig. 2 is a bottom view of Fig. 1.

Fig. 3 is an edge elevational view of Fig. 2.

Fig. 4 is a sectional view on the line 4—4 of Fig. 2.

Fig. 5 is a transverse sectional view taken on the line 5—5 of Fig. 4.

Fig. 6 is a perspective view of one portion of the device.

Fig. 7 is a perspective view of another portion of the device.

Fig. 8 is a fragmentary horizontal sectional view taken on the line 8—8 of Fig. 5.

Fig. 9 is a perspective view of one of the keying elements used in the indicator mechanism.

The automatic lock operation indicator for keys is used in conjunction with a key bit 10. A cylindrical member 11 is mounted on the base end of the key bit 10 and is formed with a circumferential groove 12. A pin 13 is arranged within the groove at one point thereof. A shell 14 is provided with a skirt wall 14^a engaging about the cylindrical member 11 and over the

said groove 12, and with an end wall 14^b formed with an arcuate opening 15 through which a portion of the end of the said cylindrical member 11 may be seen. A handle 16 for the key bit 10 is mounted on the end wall 14^b. 5

A pair of keying elements 17 is arranged in the groove 12 and engage into restricted slots 18 formed in the said skirt wall 14^a. These keying elements 17 form abutments for the pin 13 to limit relative turning of the cylindrical member 11 and shell 14 from said first mentioned position to one in which a different portion of the end of said cylindrical member 11 may be seen. Markings are arranged on the end of the cylindrical member 10 and comprise the word "Closed" 15 indicated by reference numeral 19 and the word "Open" indicated by reference numeral 20. A casing 21 is used for covering the cylindrical member 11. This casing has a skirt wall 21^a which engages over the circumference of the 20 cylindrical member, and an end wall 21^b engaging over an end area of the skirt wall 14^a and the cylindrical member 11.

A means is provided for releasably holding the cylindrical member 11 in specific relative positions with respect to the shell 14. This means includes a small expansion spring 23 engaged within an opening 24 formed inwards from the free end of the cylindrical member 10. A small ball 25 is rested upon the outer end of the spring 20 30 23 and is forced outwards and engages one of several semi-spherical recesses 26 formed on the inner face of the end wall 14^b of the shell.

The key bit 10 is of conventional form to engage and operate the tumblers or bolt of a lock, 35 depending merely on the design thereof. The bit 10 is supported on the cylindrical member 11 by engaging between small flanges 26' formed upon the end of the cylindrical member. A fastening element 27 engages between the flanges 26' and 40 the key bit for holding these parts together. The handle 16 is secured to the shell 14 by reason of engaging between parallel flanges 28. A fastening element 29 is engaged between these flanges and the handle 16 for holding these parts 45 together. The casing 21 frictionally maintains its position over the parts as illustrated in Figs. 4 and 8. The keying elements 17 are of sufficient depth to extend through the grooves 12 and through the slots 18. 50

The operation of the device is as follows:

Assume the article to be in the condition shown in Figs. 1 and 5 of the drawing. In this condition the word "Closed" is viewable through the arcuate opening 15. When the key is inserted in 55

a lock to operate the lock, the bit portion 10 engages in the lock and the person is required to turn the key by turning the handle 16. The small ball 25 engage in one of the recesses 26 5 produces sufficient resistance to cause all of the parts to maintain relatively stationary positions during the turning of the key to open a lock.

But when the key reaches the end of its opening position a small additional turn on the handle 10 16 will cause the handle 16 to turn the shell 14. At this instant the ball 25 rides out from one of the recesses 26. The shell 14 continues to be turned relative to the cylindrical member 11 which is now held stationary by the lock until 15 one of the keying elements 17 strikes the pin 13. This may be better understood by examining Fig. 5 and imagining the shell 14 to be turned anti-clockwise. As the shell turns in this direction it carries the keying element 17 along with it until 20 the latter strikes the pin 13. Then the shell may be turned no further. At this position the ball 25 will re-engage in one of the recesses 26. The key may now be removed from the lock.

When the key is examined it will be found that 25 the word "Open" is now viewable through the arcuate opening 15. A person walking away and then desiring to know whether or not the door has been left open or closed, merely inspects his key and upon the seeing the word "Open" knows 30 that the lock is open.

When the lock is closed the operation of the indicator is substantially the same as before, except for the fact that the parts are turned back to their original positions in which the word 35 "Closed" now appears through the arcuate opening 15.

With the arrangement of the parts as shown on the drawing it is required that the shell 14 be turned through 180° for changing the indication 40 from "Closed" to "Open" and vice versa. There are two recesses 26 arranged to engage the ball 25 in these particular positions. When the shell 14 is turned through 90° the ball 25 will engage another one of the recesses 26 and in this condition 45 the indicator is neutral and no indications are viewable through the opening 15. There may be occasions when it is required that the key be set to the neutral position. It is for this reason that the extra position is provided.

50 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

60 1. An automatic lock operation indicator for keys, comprising a key bit, a cylindrical member mounted on the base end of said key bit and having a circumferential groove with a pin in one point thereof, a shell having a skirt wall engaging 65 about said cylindrical member and over said groove and an end wall formed with an arcuate opening through which a portion of the end of said cylindrical member may be seen, a handle for the key bit mounted on said end wall, keying 70 elements mounted in said groove and engaging in restricted slots formed in said skirt wall and forming abutments for said pin to limit relative turning of said cylindrical member and shell from said first mentioned position to one in which a different portion of the end of said cylindrical 75 member

member may be seen, and markings to indicate "Open" and "Closed" on said portions.

2. An automatic lock operation indicator for keys, comprising a key bit, a cylindrical member mounted on the base end of said key bit and having a circumferential groove with a pin in one point thereof, a shell having a skirt wall engaging about said cylindrical member and over said groove and an end wall formed with an arcuate opening through which a portion of the end of said cylindrical member may be seen, a handle for the key bit mounted on said end wall, keying elements mounted in said groove and engaging in restricted slots formed in said skirt wall and forming abutments for said pin to limit relative turning of said cylindrical member and shell from said first mentioned position to one in which a different portion of the end of said cylindrical member may be seen, markings to indicate "Open" and "Closed" on said portions, and a casing for covering said cylindrical member.

3. An automatic lock operation indicator for keys, comprising a key bit, a cylindrical member mounted on the base end of said key bit and having a circumferential groove with a pin in one point thereof, a shell having a skirt wall engaging about said cylindrical member and over said groove and an end wall formed with an arcuate opening through which a portion of the end of said cylindrical member may be seen, a handle for the key bit mounted on said end wall, keying elements mounted in said groove and engaging in restricted slots formed in said skirt wall and forming abutments for said pin to limit relative turning of said cylindrical member and shell from said first mentioned position to one in which a different portion of the end of said cylindrical member may be seen, markings to indicate "Open" and "Closed" on said portions, and a casing for covering said cylindrical member, said casing having a skirt portion engaging over the circumference of the cylindrical member, and an end wall portion engaging over a portion of the shell and a portion of the cylindrical member.

4. An automatic lock operation indicator for keys, comprising a key bit, a cylindrical member mounted on the base end of said key bit and having a circumferential groove with a pin in one point thereof, a shell having a skirt wall engaging about said cylindrical member and over said groove and an end wall formed with an arcuate opening through which a portion of the end of said cylindrical member may be seen, a handle for the key bit mounted on said end wall, keying elements mounted in said groove and engaging in restricted slots formed in said skirt wall and forming abutments for said pin to limit relative turning of said cylindrical member and shell from said first mentioned position to one in which a different portion of the end of said cylindrical member may be seen, markings to indicate "Open" and "Closed" on said portions, and means for releasably holding the cylindrical member fixed in position relative to the shell.

5. An automatic lock operation indicator for keys, comprising a key bit, a cylindrical member mounted on the base end of said key bit and having a circumferential groove with a pin in one point thereof, a shell having a skirt wall engaging about said cylindrical member and over said groove and an end wall formed with an arcuate opening through which a portion of the end of said cylindrical member may be seen, a handle for the key bit mounted on said end wall, keying elements mounted in said groove and engaging in restricted slots formed in said skirt wall and

5 forming abutments for said pin to limit relative turning of said cylindrical member and shell from said first mentioned position to one in which a different portion of the end of said cylindrical member may be seen, markings to indicate "Open" and "Closed" on said portions, and means for releasably holding the cylindrical member fixed in position relative to the shell, including a 10 spring urged pawl mounted on one of the parts and engageable with recesses formed in the other of the parts.

15 6. An automatic lock operation indicator for keys, comprising a key bit, a cylindrical member mounted on the base end of said key bit and having a circumferential groove with a pin in one point thereof, a shell having a skirt wall engaging about said cylindrical member and over said groove and an end wall formed with an arcuate opening through which a portion of the end of said cylindrical member may be seen, a handle for the key bit mounted on said end wall, keying elements mounted in said groove and engaging in restricted slots formed in said skirt wall and forming abutments for said pin to limit relative 20 turning of said cylindrical member and shell from said first mentioned position to one in which different portion of the end of said cylindrical member may be seen, markings to indicate "Open" and "Closed" on said portions, and means for releasably holding the cylindrical member fixed in position relative to the shell, including a spring urged pawl mounted on one of the parts and engageable with recesses formed in the other of the parts, said spring being housed within an 25 opening formed in the cylindrical member.

30 35 7. A key comprising, in combination, a key bit provided with an end section having a pair of spaced indication markings, said markings corresponding to "Open" and "Closed" states of a

lock, a key bit actuating element comprising a handle section provided with a shell portion, said end section being positioned within the interior of said shell portion, said shell being provided with an opening adapted to permit viewing of each of said indication markings upon rotation of the shell to positions such that each marking is in registration with said opening, means common to said end section and shell portion for normally maintaining said bit and actuating element fixed 10 related during lock operation and permitting continued rotation of the shell portion after a lock is actuated, and additional means common to said end section and shell portion for preventing said continued rotation of said shell portion after a 15 predetermined arc of motion.

8. In a key of the lock operation indicator type, a key bit provided with an indicator section, said section having spaced indicia on a surface thereof to indicate "Open" and "Closed" 20 lock positions of the key bit, a handle for said key bit provided with a shell section, said indicator section being positioned within the shell section interior, said shell section being provided with an opening located to be in registration with either of said spaced indicia upon rotation of said handle with respect to said key bit, spring-actuated means common to said indicator section and the said shell section for normally maintaining said key bit and handle in fixed relation 25 during the actuation of a lock, said means being constructed to permit rotation of the handle with respect to the key bit subsequent to lock adjustment, and auxiliary means operatively associated with the shell section and indicator section for 30 preventing said last named rotation after a predetermined arc of rotation. 35
